MACHINE TO ASSEMBLE BOLT FLANGES IN
HUB SHELLS AND PIERCE EIGHT RIVET
HOLESHerman Tormyn and Frank F. Wiethoff, Detroit,
Mich., assignors to General Motors Corpora-
tion, Detroit, Mich., a corporation of Delaware

Application July 29, 1932. Serial No. 625,995

15 Claims. (Cl. 164—90)

This invention relates to the manufacture of wire wheels and has particular reference to a machine or die to assemble the bolt flange inside a hub shell and to pierce a plurality of rivet holes in the flange and shell. The machine or die of the present invention is one of a series of ten and in sequence of operation follows the die of our copending application, Serial No. 625,994, filed July 29, 1932.

10 The die of the invention comprises a lower die shoe and a top shoe. The wheel hub with the bolt flange placed therein are positioned in the lower or die shoe and the top shoe caused to descend thereon firmly to press the bolt flange into the hub shell and to cause the operation of the punches to punch rivet holes in the assembled bolt flange and shell.

On the drawings:

Figure 1 is a front view of the press with the die 20 of the invention applied thereto.

Figure 2 is a side view of the structure of Figure 1.

Figure 3 is an enlarged detailed sectional view taken substantially on the line 3—3 of Figure 6 25 showing the top shoe or die on the lower die and showing the punches as having punched the rivet holes.

Figure 4 is a view similar to Figure 3 but showing the top die separated from the die shoe.

30 Figure 5 is a section on the line 5—5 of Figure 3.

Figure 6 is a plan view of the lower die shoe taken on the line 6—6 of Figure 4, with parts broken away and shown in section clearer to illustrate the structure.

35 Figure 7 is a perspective view of the ring acting as a retainer for the punch holders and as a seat for the punch holders and as a seat for the wheel hub.

Figure 8 is a perspective view of the element 40 which guides the backing members for the punches.

Figure 9 is a perspective view of one of the backing members for the punches.

Figure 10 is a perspective view of one of the retaining blocks forming the pivotal bearing for the backing members.

Referring to the drawings, the numeral 2 indicates the machine or press of the invention as a whole. The press comprises the upright frame 50 at the upper portion of which an electric motor 4 is mounted. The motor has the driving pulley 6 which drives a belt 8 which in turn drives a flywheel 10 rigidly mounted on the axle 12 which extends across the frame of the machine and at 55 the opposite side has a gear wheel (not shown)

mounted thereon which meshes with and drives the large gear 14 rigidly mounted on the shaft 16 having a crank 18 intermediate its ends. The crank 18 has attached thereto the connecting rod 20 which operates the crosshead 22 suitably attached to the top shoe 24 of the die. The lower or die shoe is indicated at 26 and a part thereof is resiliently mounted by means of a hydro-pneumatic cushion indicated as a whole at 27. The cushion comprises the cylinder 28 having a piston therein connected to a piston rod 30 secured to a lower plate 32. Suitable pins 33 connect the plate 32 with a plate 34. Suitable pressure pins 36 abut at their lower ends against the plate 34 and at the upper ends against the bottom of 60 the slide holder 38 (Figures 3 and 4). This structure gives a resilient or hydro-pneumatic mounting to the slide holder.

A handle 40 operating a linkage system 42 operates a suitable clutch (not shown) which 75 causes the small gear on the end of the shaft 12 to be engaged with the shaft and to rotate the gear 14. After one operation of the punch a suitable throw-out mechanism will throw the clutch out of engagement with the gear. This 80 mechanism is not shown but is conventional and well known in the art. A suitable brake drum is shown at 44 having brake shoes 46 operated from a suitable linkage 48.

The parts so far described are conventional 85 and are well known in the art of presses.

Referring to Figures 3 and 4, the lower die shoe comprises the flat lower member 50 having openings 52 for the free passage of the pressure pins 36 and a smaller conical opening 54 to allow the slugs or punched-out metal to fall to the base of the machine. A second annular element 56 is secured to the lower member 50 by means of the machine bolts 58. Ears 60 at the side of the member 56 have rigidly mounted 90 therein the guide bolts 62 which project upwardly and away from the die shoe 26 and slide in bearings 64 mounted in the ears 66 of the top die member 24.

The upper member 56 of the lower die shoe 100 26 is formed with eight flat surfaces 68 at its inner periphery (see Figure 6) and against the flat peripheries there are secured the cam members 70 and 72 functioning in pairs and having the inner surfaces 74 inclined as is best shown 105 in Figures 3 and 4. The cam members 70 and 72 are spaced at their adjacent edges, as shown in Figure 6, and have the flanges 76 extending toward each other. As many pairs of these cam blocks 70 and 72 are used as it is desired to 110

punch holes in the shell and bolt flange. In the present instance eight of these pairs of blocks are used. Each cam block 70 or 72 is rigidly secured to the member 56 by means of the machine 5 bolts 78.

Mounted to slide on the interior periphery of the member 56 of the die shoe is the annular tool holder slide 38. The slide 38 has a lower projecting flange or extension 82 which cooperates with a shoulder 84 formed on the member 56 to limit the upward movement of the slide 38. The pressure pins 36 press against the bottom of the slide 38 and constantly urge it upward to the position shown in Figure 4. Suitable openings 86 in the slide 38 accommodate guide pins 88 permanently mounted in the lower member 50 of the base and serve to guide the slide 38 in a definite position.

The upper end of the slide 38 is divided circumferentially into eight grooves 90 (Figure 6) and at each groove there is slidably a punch holder 92. Each punch holder has a tongue 94 at its end and two rollers 96 are mounted on an axle 98 extending through the tongue. The rollers extend to the rear of the flanges 76 on the cam blocks 70 and 72 while finished shoulders 100 on the punch holders 92 cooperate with finished portions 102 on the surfaces 74 of the cam blocks. Segments 104 on the top of the punch holder slide 38 form the recesses 90 between them and on the top of each segment 104 there is a rib 106. The rib 106 fits into a groove 108 formed on the underside of the retaining ring 110 (Figure 7) positioned on top of the slide 38 and having grooves 112 in which fit the upper portion of the punch holders 92. The inner periphery of the retaining ring 110 is shaped as shown at 114 to receive the wheel hub shell 116. The interior end of each punch holder 92 has a punch 124 mounted therein and held in place by a set screw (not shown). A passage 126 is provided to allow the insertion of a tool to knock out the punch.

The ring 110 has an inclined passage 118 in which there is held a coil spring 120 which urges a pin 122 into the surface at 114. The purpose of the pin is to locate the hub shell, the pin fitting into one of the short spoke openings.

Below each punch holder 92 a passage 128 is formed in the punch holder slide 38. A coil spring 130 is held in each passage and pushes a headed pin 132 inwardly toward the center. The purpose of these spring pressed pins will be later described.

The punch holder slide 38 has its center bored as indicated at 134, and this bore is considerably enlarged at the upper portion as indicated at 136. In the bore 136 there is mounted the bearing ring 138 secured to the punch holder slide 38 by means of the machine bolts 140. The upper portion of the bearing ring 138 has segmental portions 142 thereon from which the metal has been removed to give an inclined surface, as is best shown in Figure 3. Below each inclined surface 142 a passage 144 is provided which cooperates with passages 146 in the holder slide 38 the purpose of the inclined portions and passages being to allow the punched-out metal to fall to the base of the machine in case this piece of punched-out metal should fall on top of the bearing member 138.

The bearing ring 138 has the shoulder 148 which cooperates with a shoulder 150 on a guiding element 152 (Figure 8), to hold the guiding element rigidly in position. The guiding ele-

ment 152 has the tines 154 which extend upwardly substantially to the top of the slide holder 38. In the spaces between the base of the tines 154, indicated at 156 at Figure 8, there are mounted the bearing blocks 160 shown in perspective in Figure 10. The bearing blocks 160 have a shoulder 162 with which there cooperates a retaining ring 164 which holds the bearing blocks in place.

The bearing ring 138 and the bearing blocks 160 have cooperating bearing surfaces indicated at 166 and 168, respectively, in which there is received the bearing portion 170 of a backing member 172 (Figure 9) which is of sufficient width to allow it easily to slide between the tines 154 of the element 152. There are eight backing members 172 and each has a shoulder 174 which cooperates with the bearing block 160 to limit the inward movement of the backing member. A tongue 176 on the outer side of the backing member 172 slides over the lip 178 formed on the bearing ring due to the machine portions 142 and acts as a guard for the bearing to prevent any chipped metal from getting into the bearing. In the swinging movement the tongue 176 will ride over the lip 178 and any foreign matter falling in the space between the backing members and the slide 38 will be diverted by the tongue 176 to the openings 144. The backing members 172 are constantly urged inwardly by the springs 130 pressing against the pins 132 as is clearly shown in Figures 3 and 4.

The upper portion of each backing member 172 has mounted therein the hardened wear member or die 180 which is hollow and which cooperates with the punches 124. When the machine is in operation the backing member 172 will be on one side of the hub shell and bolt flange while the punch 124 will be on the other so that when the punch 124 acts it will punch out the metal into the bore of the wear resisting member 180. Each wear resisting member 180 is held in position by a set screw (not shown). In back of each wear resisting member 180 the backing member 172 has the recess 186 which is tapered so that the punched-out piece of metal will fall toward the center of the die and down through the bore 134, conical portion 54, to the base of the machine.

The bolt flange of the wheel hub is indicated at 188 and is placed in the shell 116 before the shell is positioned on the lower die 26.

The upper or top die 24 has the head 190 movably secured thereon by means of the machine bolts 192 threaded into the head 190 and having the shanks slidably in openings 194 in the top die 24. The head 190 is spring pressed away from the top die 24 by means of a plurality of coil springs 196, preferably three in number, mounted in recesses in the top die 24 and in the head 190. The springs 196 rectify any inaccuracy in the positioning of the hub shell and flange in the die shoe for at times they may not be evenly positioned. The shape of the lower portion of the head 190 and 198 is made to conform to the interior portion of the hub shell 116 and to cooperate with the shaped portion 114 on the retainer ring 110. This is best shown in Figure 3.

The movable head 190 has a central opening to allow the shank 200 of a spreader cam 202 to extend therethrough. The purpose of the spreader cam 202 is to spread or force the backing members 172 from the position shown in 150

Figure 4 to that shown in Figure 3 when the top die 24 descends on the lower die shoe 26.

Mounted at the front and rear of the top die 24 are the fingers 204 pivoted between ears 206 on a bracket 208 secured to the top die 24. Coil springs 210 are positioned between the upper end 212 of the spring and the head while the downward end 214 has a hook 216 thereon. As many of these fingers as desired may be used but in actual practice it has been found that three are sufficient, two closely together at one side and one at the opposite side. The purpose of these fingers is to grip under the edge flange 218, as shown in Figure 4, when the top die descends so that it will raise the wheel hub and punched bolt flange when the head 24 rises. The springs 210 are of sufficient strength to press the fingers inwardly so that the top die 24 will carry the wheel hub shell upwardly therewith. The hub shell may be removed by grasping it with the hand and pulling it from the machine. In its dotted line position in Figure 4, the finger 204 is a little out of position better to illustrate its structure and application.

Suitable spacers 220 are placed around the guide rods 62 and cooperate with the bearings 64 to limit the downward movement of the top die 24 relative to the lower die 26. The purpose of this limitation of movement is to prevent the movable head 190 and the retaining ring 110 from crushing the metal of the hub shell held therebetween. The cooperative interrelation and position of all of these parts is shown in Figure 3 and the arrangement or spacing is so fixed that the spacer 220 and bearing 64 will come in contact at a time to prevent the crushing action on the wheel hub between the movable head 190 and the retaining ring 110.

A guard 221 is secured to the die shoe to prevent slugs and foreign matter getting to the working parts.

The operation of the die is as follows:

Referring to Figure 4 the position of the parts is shown before the top die or shoe is caused to descend on the lower die shoe to cause the punches to operate. The hub shell 116 and bolt flange 188 are of course placed in the lower or die shoe 26. The operator then moves the handle 40 to cause the machine to perform one operation or one reciprocation of the top die 24. The machine is so arranged that it will be thrown out of operation after one reciprocation of the top die. The first part of the descent of the top die 24 will cause two things: (1) The pneumatic part of the hydro-pneumatic cushion will be in action and cause the head 190 firmly to press the bolt flange 188 into the hub shell 116, or to the position shown in Figure 3. (2) The spreader cam 202 to contact with the inner edges of the backing members 172 to force them inwardly against the inner edge of the bolt flange 188 and pushing the plungers 132 outwardly as shown in Figure 3. When the shank portion 200 of the spreader die 202 reaches the spreader members, they will be held in a definite position. After the bolt flange 188 has been pressed into the wheel hub the continued downward movement of the top shoe will be against the full resistance of the hydro-pneumatic cushion, the resistance pressure now being very much increased. The continued downward movement will now force the slide holder 38 downward against the full pressure on the pressure pins 36 and cause the punch holders 92 to ride on the cam blocks 70 and 72 to force the punch holders inwardly and cause the punches 124 to punch

rivet holes 222 in the shell 116 and bolt flange 188. In punching the holes the metal from the hub shell will be crowded or pushed into the bolt flange at the abutting edges of the openings rigidly to hold both together. The punched metal will be received in the wear member 180, pushed through the bore of the wear member, and fall from the recess 186 to the center of the machine and down through the passage 134 into the conical portion 54 and to the base of the machine. If for any reason the punched-out pieces of metal should fall on top of the bearing ring 138, they will be directed by the inclined surfaces 142 into the passage 144, 146 and fall to the base of the machine. When the punches have performed their work the top die 24 will rise which will allow the pins 36 to push upward and force the slide holder 38 upward and carry therewith the punch holders 92. The rollers 96 on the punch holders will now ride on the flanges 76 of the cam blocks 70 and 72 to withdraw the punch holders rearwardly or out of the punched holes 222. When the shank 200 of the spreader cam leaves the backing members 172, the springs 130 and plungers 132 will again force the backing members 172 inwardly to the position shown in Figure 4. The fingers 214 have ridden over the edge of the flange 218 on the hub into suitable recesses or cut out portions in the retainer ring 110 and the slide holder 38 and will be underneath the flange and pull the assembled hub and bolt flange upwardly therewith to the position shown in Figure 4. The operator may now remove the punched hub shell and bolt flange from the machine and insert a new one in the lower die shoe 110 to recommence the operation.

We claim:

1. In a machine of the class described, a die shoe adapted to receive a wire wheel hub shell and bolt flange, a top shoe reciprocable relative to said die shoe, a plurality of punches adapted to punch rivet openings in said shell and bolt flange, a plurality of pivoted backing members swingable to contact with the interior of the bolt flange opposite the punches and to receive the punched-out material, the downward movement of said top shoe causing the backing members to swing on their pivots to spread inside the wheel hub shell and the punches to move to punch out the rivet holes.

2. In a machine of the class described, a die shoe adapted to receive a wire wheel hub shell and bolt flange, a top shoe reciprocable relative to said die shoe, a plurality of punch holders slideable in said die shoe, a punch in each holder pivoted means swingable to back the interior of the hub shell and flange when the punches are acting, means operating upon downward movement of the top shoe to cause the punch holders to slide toward the shell, and means operative on said downward movement to cause said backing means to swing on their pivots to contact the interior of the hub shell, said last two means operating in timed relation.

3. In a machine of the class described, a die shoe adapted to receive a wire wheel hub shell and bolt flange, a top shoe reciprocable relative to said die shoe, a plurality of punch holders slideable in said die shoe, a punch in each holder, means to back the interior of the hub shell and flange when the punches are acting, means operating upon downward movement of the top shoe to cause the punch slides to slide toward the shell, means operative on said downward movement to cause said backing means to back the interior of

- the hub shell, said last two means operating in timed relation, and means on the top shoe to pick up and pull the punched hub shell and flange from the die shoe when the top shoe is raised. 80
- 5 4. In a machine of the class described, a die shoe adapted to receive a wire wheel hub shell and bolt flange, a top shoe reciprocable relative to said die shoe, a plurality of punch holders slideable in said die shoe, a punch in each holder, pivoted 85
10 means swingable on their pivots to back the interior of the hub shell and flange when the punches are acting, means operating upon downward movement of the top shoe to cause the punch holders to slide toward the shell, means 90
15 operative on said downward movement to cause said backing means to swing on their pivots to contact the interior of the hub shell, said last two means operating in timed relation, and means to force the first-named means away from the shell 95
20 when the top die is raised.
5. In a machine of the class described, a die shoe adapted to receive a wire wheel hub shell and bolt flange, a top shoe reciprocable relative to said die shoe, a plurality of punch holders slideable in 100
25 said die shoe, a punch in each holder, means to back the interior of the hub shell and flange when the punches are acting, stationary means operating upon downward movement of the top shoe to cause the punch slides to slide toward the shell, means operating on said downward movement to cause backing means to contact the interior of the hub shell, said last two means operating in timed relation, and means on the top shoe to force the flange into the shell before the 105
30 operation of the punches.
6. In a machine of the class described, a die shoe adapted to receive a wire wheel hub shell and bolt flange, a top shoe reciprocable relative to said die shoe, a slide holder reciprocable in said 110
40 die shoe, a plurality of punch holders slideable in said slide holder, a punch in each punch holder, means to back the interior of the hub shell and flange when the punches are acting, means operating upon downward movement of the top shoe and said slide holder to cause the punch holders to move toward the shell, and means operative on 115
45 said downward movement to cause said backing means to back the interior of the hub shell, said last two means operating in timed relation.
7. In a machine of the class described, a die shoe adapted to receive a wire wheel hub shell and its bolt flange, a top shoe reciprocable relative to said die shoe, a slide holder resiliently reciprocably mounted in said die shoe, a plurality of 120
50 punch holders slideable to and from said shell in said slide holder, a punch in each punch holder, cam means for said punch holders, a plurality of backing elements pivotally mounted on said slide holder, one backing element for each punch, a 125
55 spreader cam on said top die adapted to spread the backing members against the inside of the shell and bolt flange opposite the punches, the downward movement of said top die causing the spreader cam to act on the backing members, said 130
60 downward movement also forcing the slide holder downward to cause the cam means to force the punch holders and punches to act on the hub shell and bolt flange to punch rivet holes through both. 135
65 8. In a machine of the class described, a die shoe adapted to receive a wire wheel hub shell and its bolt flange, a top shoe reciprocable relative to said die shoe, a slide holder resiliently reciprocably mounted in said die shoe, a plurality of punch holders slideable to and from said shell in 140
70 said slide holder, a punch in each punch holder, cam means for said punch slides, a plurality of backing elements pivotally mounted on said slide holder, one backing element for each punch, a spreader cam on said top die adapted to spread the backing members against the inside of the shell and bolt flange opposite the punches, the downward movement of said top die causing the spreader cam to act on the backing members, said downward movement also forcing the slide holder downward to cause the cam means to force the punch holders and punches to act on the hub shell and bolt flange to punch rivet holes through both. 145
75 9. In a machine of the class described, a die shoe adapted to receive a wire wheel hub shell and bolt flange, a top shoe reciprocable relative to said die shoe, a plurality of punch holders slideable in said slide holder, a punch in each punch holder, means on the slide holder to back the interior of the hub shell and flange when the punches are acting, means on the die shoe operating upon downward movement of the top 150

- shoe to cause the punch holders to slide toward the shell, means on the top die operative on said downward movement to cause said backing means to contact the interior of the hub shell, 5 said last two means operating in timed relation, and means to force the first-named means away from the shell when the top die is raised. 13. In a machine of the class described, a die shoe, a slide holder slidably mounted in said die shoe and adapted to receive a wire wheel hub shell and bolt flange, a top shoe reciprocable relative to said die shoe, a plurality of punch holders slidable in said slide holder, a punch in each punch holder, means on the slide holders 10 to back the interior of the hub shell and flange when the punches are acting, means on the die shoe operative upon movement of the slide holder to cause the punch slides to slide toward the shell, means operative incident to the downward movement of the top die to cause said backing means to contact the interior of the hub shell, said last two means operating in timed relation, and means on the top shoe to force the flange into the shell before the operation of the punches. 14. In a machine of the class described, a die shoe, a circular slide holder slidably mounted in said die shoe, a plurality of backing members pivotally mounted in the slide holder at the interior thereof and concentrically therewith, a 15 guiding element mounted in the slide holder to guide the backing members, spring pressed means 20 constantly urging said backing members inwardly or toward a center, a plurality of punch holders concentrically arranged in the slide holder, punches in said punch holders, a plurality of cams on the die shoe cooperating with the punch holders to cause the punch holders to move toward the wheel hub when the slide holder is moved, a top shoe reciprocable relative to the die shoe, a cam on said top shoe to spread the backing members when the top die is moved relative to the die shoe, the movement of said top die causing the movement of said slide holder to cause the punches to punch openings in the wheel hub and bolt flange. 15. In a machine of the class described, a die shoe, a top shoe spaced from said die shoe and reciprocable relative thereto, means on said die shoe adapted to receive a wheel hub and bolt flange, a plurality of punches slidably mounted on the die shoe and adapted to be moved toward the hub to punch spoke openings, a plurality of backing members pivotally mounted in the die shoe and adapted to move on their pivots to back the hub and flange when the punches are operating, and means on the top die operative when the top shoe is moved toward the die shoe to cause the backing members to move to the wheel hub to back the punches.
